UNITED STATES PATENT OFFICE

156,069

DESIGN FOR AN AIRBRUSH

Robert B. Briggs, Newton, Mass.

Application January 11, 1946, Serial No. 125,438

Term of patent 14 years

(Cl. D62—2)

To all whom it may concern:

Be it known that I, Robert B. Briggs, a citizen of the United States, residing at Newton, in the county of Middlesex and Commonwealth of Massachusetts, have invented a new, original, and ornamental Design for an Airbrush, of which the following is a specification, reference being had to the accompanying drawing, forming part thereof.

Fig. 1 is a side view of an airbrush showing my new design.

Fig. 2 shows the other side of the airbrush of Fig. 1, and

Fig. 3 is a top plan view, and Fig. 4 is an end view thereof.

I claim:

The ornamental design for an airbrush, as shown.

ROBERT B. BRIGGS.
